UNITED STATES PATENT OFFICE

127,915

DESIGN FOR A VELOCIPED

Elyert John Weller, Jr., Milwaukee, Wis.

Application October 14, 1940, Serial No. 95,831

Term of patent 14 years

To all whom it may concern:

Be it known that I, Elyert John Weller, Jr., a citizen of the United States, residing at Milwaukee, in the county of Milwaukee and State of Wisconsin, have invented a new, original, and ornamental Design for a Velocipede, of which the following is a description, reference being had to the accompanying drawing, forming part thereof.

In the drawing:

Fig. 1 is a perspective view illustrating the

front and one side of a velocipede, showing my new design; and

Fig. 2 is a perspective view showing the rear and opposite side thereof.

The dominant and characteristic features of the design are shown in solid lines.

I claim:

The ornamental design for a velocipede, substantially as shown and described.

ELYERT JOHN WELLER, JR.
